UNITED STATES PATENT OFFICE.

JOHN W. SNYDER AND JOSIAH C. McMAHON, OF PITTSBURG, PENNSYLVANIA.

TRAP-DOOR FOR RAILWAY-CARS.

SPECIFICATION forming part of Letters Patent No. 472,003, dated March 29, 1892.

Application filed September 28, 1891. Serial No. 407,062. (No model.)

To all whom it may concern:

Be it known that we, JOHN W. SNYDER and JOSIAH C. McMAHON, citizens of the United States, residing at Pittsburg, in the county of 5 Allegheny and State of Pennsylvania, have invented certain new and useful Improvements in Trap-Doors for Railway-Cars; and we do hereby declare the following to be a full, clear, and exact description of the invention, 10 such as will enable others skilled in the art to which it pertains to make and use the same, reference being had to the accompanying drawings, which form a part of this specification.

15 Our invention relates to an improvement in sliding trap-doors for railway-cars; and it consists in certain details of construction and combination of parts, as will be fully described hereinafter.

20 In the accompanying drawings, Figure 1 is an inverted plan view of the bottom of an ordinary railway-car having our improved sliding trap-doors arranged in position thereon. Fig. 2 is a sectional end elevation of the 25 same. Fig. 3 is an enlarged detailed side elevation of one of the end guides and the bar upon which the same slides. Fig. 4 is an inverted plan view of the same.

To put our invention into practice with an 30 ordinary railway-car 1, having two longitudinal openings 3 arranged in the floor of the same, we secure to the beams 9 two timbers 8, to the inner sides of which are attached two guide-bars 11, which are held in position by 35 bolts 12. Operating on these guide-bars 11 are two sliding doors 2, capable of being moved toward or away from each other for the purpose of covering or uncovering the openings 3, formed in the floor of the car 1. Attached 40 to each end of these doors 2 are two grooved plates 10, (see Figs. 3 and 4,) which serve to guide the said doors evenly when moving the

same. Attached to the frame of the car by means of bearings 7 and at the middle of the length of the doors 2 is a shaft 5, having 45 square ends for the purpose of attaching a crank 6 thereto. This shaft 5 is attached to the doors 2 by means of bearings 7, and the said shaft is provided with a right and left hand screw-thread, which operates in threads 50 formed in the two outer bearings 7. These two last-mentioned bearings 7 are firmly attached in position by means of bolts extending through the doors 2 vertically and horizontally. To operate these doors, it is only 55 necessary to place the crank 6 in position at either end of the threaded shaft 5 and turn the same in the proper direction, which will open or close the doors, as desired.

Having thus described our invention, what 60 we claim, and desire to secure by Letters Patent, is—

The herein-described trap-doors for railway-cars, consisting of the doors 2, arranged to cover openings formed in the bottom of the 65 car, the cross-beams 8, having attached thereto the guide-bars 11, the grooved guide-plates 10, attached to each angle of the doors, the shaft 5, having a right and left hand thread, secured in bearings to the frame of the car 70 and to the doors in a manner that when the said shaft is revolved the doors will move toward or away from each other in either direction, all arranged and combined for service substantially as and for the purpose set forth. 75

In testimony that we claim the foregoing we hereunto affix our signatures this 24th day of September, A. D. 1891.

JOHN W. SNYDER. [L. S.]
JOSIAH C. McMAHON. [L. S.]

In presence of—
JOHN S. KENNEDY,
I. A. CARLINE.
